DESIGN FOR A BATHTUB

Clarence J. Rodman, Alliance, Ohio

Application March 13, 1946, Serial No. 127,417

Term of patent 14 years

(Cl. D4—4)

To all whom it may concern:

Be it known that I, Clarence J. Rodman, a citizen of the United States, residing at Alliance, in the county of Stark and State of Ohio, have invented a new, original, and ornamental Design for Bathtub, of which the following is a specification, reference being had to the accompanying drawing, forming part thereof.

Fig. 1 is a view in perspective of a bathtub showing my new design, Fig. 2 is a sectional view through the center thereof, and Fig. 3 is a section on the line 3—3 of Fig. 1.

The dominant feature of my design for a bathtub resides in the configuration presented by the stepped, recessed paneling arrangement disposed at either end of the skirt element.

I claim:

The ornamental design for a bathtub, substantially as shown and described.

CLARENCE J. RODMAN.
